James R. Robinson, Inventor

UNITED STATES PATENT OFFICE.

JAMES R. ROBINSON, OF MONONGAHELA CITY, PENNSYLVANIA.

OILER FOR WHEELS.

SPECIFICATION forming part of Letters Patent No. 621,850, dated March 28, 1899.

Application filed May 11, 1898. Serial No. 680,379. (No model.)

To all whom it may concern:

Be it known that I, JAMES R. ROBINSON, a citizen of the United States, residing at Monongahela City, in the county of Washington 5 and State of Pennsylvania, have invented a new and useful Oiler for Car-Wheels, Loose Pulleys, &c., of which the following is a specification.

My invention relates to oiling devices for 10 car-wheels, loose pulleys, and other mechanical contrivances adapted to run loosely on their shafts and which require to be lubricated; and the object of the invention is to provide a simple device which may be easily 15 and quickly applied to the structure which it is desired to lubricate, which will effectually retain the oil within the chamber of the wheel or pulley against any tendency to be spilled outward by centrifugal force when the 20 pulley is in motion, and which provides for the introduction of the lubricant to the oil-chamber in an easy and expeditious manner.

With these ends in view my invention consists in the novel construction and arrangement of parts, which will be hereinafter fully described, and pointed out in the claims.

To enable others to understand the invention, I have illustrated the same in the accompanying drawings, forming a part of this 30 specification, and in which—

Figure 1 is an elevation looking at one side of a mining-car wheel to which my improved oiler is applied. Fig. 2 is a vertical sectional elevation taken transversely through the 35 wheel and the oiling device, the plane of section being indicated by the dotted line 2 2 of Fig. 1. Fig. 3 is an enlarged view in elevation of the oiling device detached from the car-wheel or loose pulley to which it may be 40 applied. Fig. 4 is an end elevation of the oiling device, looking at the face of the closure-plug thereof. Fig. 5 is a longitudinal sectional elevation through the oiling device 45 on the plane indicated by the dotted line 5 5 of Fig. 3.

Like numerals of reference denote like and corresponding parts in each of the several figures of the drawings.

The oiling device of my invention is designated in its entirety by the numeral 1 in the accompanying drawings. One of the principal parts of this oiling device is a tubular

shell or body 2, which constitute a valve-casing that serves to normally close the inlet-port to the oiler device, and the outer end 55 of said tubular shell, body, or valve-casing 2 is enlarged to form a plug 3, which is adapted to be screwed into a threaded opening in the car-wheel, pulley, or other device to which the oiler is to be applied, so that said plug 60 of the tubular shell or valve-casing serves to close the opening provided in the oil-chamber for the reception of the oiler device. This enlarged end or plug is of greater diameter than the tubular shell or valve-casing, and it is 65 made integral therewith, thus simplifying the construction and facilitating the manufacture of this device. The plug-shaped end 3 of the oiling device is provided with an external thread 4 of the variety known to the art as a 70 "pipe-thread," and in the exposed face of this plug 3 is formed a cavity 5, into which may be thrust the spout of an oil-can when it is desired to replenish the supply of lubricant to the oil-chamber of the car-wheel or other 75 structure. The inner part of the cavity 5 in the plug of the tubular shell is contracted in diameter by the formation of a flange 6, and the inner face of this flange is shaped or fashioned to form a valve-seat at one end of 80 the chamber in the tubular body or valve-casing 2. An inlet or filling port 8 is formed by this flange 6, which port lies in axial relation to the tubular shell, and said port opens into the valve-casing or body through 85 the valve-seat 7, which is formed by the said flange 6. At the inner or rear end of the shell or casing 2 is formed an external screw-thread 9, and against the open inner end of the shell or casing is applied an imperforate 90 cap 10. This cap is formed with an annular internally-threaded flange 11, which is screwed upon the externally-threaded end 9 of the shell or casing, and said flanged cap is thus adapted to lie concentric with the enlarged 95 threaded plug 3 of the shell or casing, so that the oiling device in its entirety may be readily introduced into or withdrawn from the oil-chamber of a car-wheel, pulley, or other contrivance. The imperforate cap is of a diameter corresponding to the enlarged plug-shaped 100 end of the casing or shell, and it forms a seat against which one of a coiled spring is adapted to bear or press.

Within the chamber of the tubular shell or casing is loosely fitted a cup-shaped metallic valve 12, which is preferably semispherical in form and of a diameter to play freely in 5 the valve-casing in an endwise direction therein, and the convex imperforate face of this cup-shaped valve is adapted to fit snugly against the annular valve-seat 7 between the chamber of the shell and the cavity 5 in the 10 plug 3. The concave side of this cup-shaped valve faces toward the fixed cap 10, which is secured to the rear end of said shell, and between said valve and the cap is arranged a coiled pressure-spring 12^a. One end of this 15 spring is housed and seated within the cup-shaped valve to be held in place thereby, so as to maintain the spring normally in an active position to press the valve firmly against the seat, and thereby close the filling-port 8 20 against the passage and leakage of the lubricant from the chamber of the wheel or pulley. The other end of this spring is fitted or seated against the fixed cap 10, which, it will be observed, is secured removably to the shell 25 or casing, so that the spring and valve may be withdrawn for the purpose of replacing the parts whenever necessary. The tubular shell or casing 2 of the oiler is provided at one or more points between the enlarged plug 30 3 and the fixed removable cap 10 with one or more radial exit-ports 13, which establish communication between the tubular shell of the insertible oiling device and the lubricating-chamber of the wheel or pulley.

35 My oiling device may be used generally in the arts—as, for instance, in connection with a car-wheel, a pulley, or any other mechanical contrivance adapted to rotate on the shaft or axle and which requires lubrication for its 40 free running thereon in order to reduce the friction and wear to a minimum. As an exemplification of the invention I have illustrated it as applied to a car-wheel by Figs. 1 and 2 of the drawings, in which the numeral 45 14 indicates the wheel, 15 the hub thereof, 16 an oil-chamber in close relation to the hub, and 17 a port or channel which leads from the oil-chamber to the journal or axle opening of the hub. The oil-chamber 16 may consist 50 of a single continuous chamber extending entirely around the hub, or said oil-chamber may be divided into two or more compartments adapted to communicate one with the other or to communicate individually with the shaft or axle opening in said hub. In Fig. 1 this oil-chamber is shown as consisting of two compartments, in one of which is provided a threaded opening 18, into which may be screwed the threaded plug 3 of the tubu- 55 lar shell or casing forming a part of the oiler device, while the other oil-chamber is adapted to be closed by a suitable plug. It will be understood, however, that the oil chamber or chambers are not a material part of the present improvement, which resides in the insertible oiler device that is peculiarly con-

structed for expeditious application to the wheel or pulley.

In my invention the parts are separably coupled together to facilitate their assembly and disconnection. The tubular shell or casing, which is open at its rear end, enables the cup-shaped valve to be readily placed therein for its convex face to rest against the valve-seat, and the coiled spring 75 may then be fitted in said casing or shell for one end of the spring to enter the cavity in said valve, which serves to retain the spring in proper central relation to the valve, and, finally, the imperforate cap is screwed to the 80 threaded rear end of the body or casing in order to hold the spring in place and to compress the spring sufficiently for holding the valve firmly against its seat at the open end of the casing. As the imperforate cap 10 lies 85 flush with the threaded enlarged plug of the casing or shell, the oiler device after its parts shall have been assembled may readily be thrust through the opening 18 and into the lubricating-chamber of the wheel or pulley, 90 and by turning the casing or shell the threaded enlarged plug 3 may be screwed into the opening 18 for the purpose of securely holding the oiler device in position within the chamber. The spring serves to tightly hold the cup-shaped valve against the seat at the open end of the casing, so that the lubricant is effectually retained within the chamber against any tendency to fly outwardly and escape under the centrifugal force developed by rotation of 95 the wheel or pulley; but the spout of an oil-can may readily be introduced through the cavity 5 of the plug to press the valve inwardly and permit the lubricant to be supplied to the chamber of the tubular body, 100 from whence the oil is free to pass through the radial ports 13 into the oil-chamber 16, thus enabling the supply of lubricant in the chamber 16 to be easily and quickly replenished.

110 A further advantage of my improved construction resides in the arrangement of the spring and valve to make the cup-shaped valve embrace the spring for a portion of its length, so that the spring serves the purpose 115 of a stem and normally forces the valve to its seat. A separate guide-stem and a boss for said stem are dispensed with in my invention, and the valve and the spring are mutually adapted to each other to hold themselves 120 in proper alignment. The valve is arranged to present its convex face to the filling-port, and this convex valve-face serves as a deflector to direct the oil from the oil-cup into the valve-shell.

125 I do not strictly confine myself to the employment of a metallic cup-shaped valve, as it is evident that valves of other materials may be used, and, if desired, the lubricating chamber or chambers 16 may contain a suitable packing—such, for example, as cotton-waste.

It will be understood that changes in the form and proportion of parts may be made by a skilled mechanic without departing from the spirit of the invention.

5 Having thus described the invention, what I claim is—

1. In an insertible oiler device, the combination with a valve-shell having a filling-port and a seat, of a stemless cup-shaped valve snugly fitted in the shell to present a convex deflector-face to the seat, a cap at the opposite end of said shell, and a coiled spring having one end embraced by the chambered cup-shaped valve and its other end seated against the cap, said valve and spring being arranged mutually to retain each other in place and the spring serving as a guide-stem for the valve substantially as described.
- 10 2. An insertible oiler device comprising a

shell having at one end a threaded plug 20 formed with a cavity and with an internal flange constituting a valve-seat and a filling-port, a cup-shaped valve fitted snugly within the shell to travel across lateral ports therein and arranged for its convex face to bear firmly 25 against the valve-seat, a coiled spring confined at one end within the cup-shaped valve to insure connection of the parts, and a cap screwed to the inner end of the shell and forming a bearing for one end of said spring, sub- 30 substantially as described.

In testimony that I claim the foregoing as my own I have hereto affixed my signature in the presence of two witnesses.

JAMES R. ROBINSON.
